[57] **CLAIM**

The ornamental design for a combined shower stall base and sliding door unit or the like, as shown and described.

DESCRIPTION

FIG. 1 is a side view, partly in section, of a combined shower stall base and sliding door unit or the like showing my new design;

FIG. 2 is a top plan view thereof;

FIG. 3 is front view thereof;

FIG. 4 is an enlarged fragmentary front elevational view thereof;

FIG. 5 is an enlarged fragmentary rear perspective view thereof;

FIG. 6 is an enlarged fragmentary front perspective view thereof;

FIG. 7 is an enlarged fragmentary top plan view thereof with the guide bar omitted for convenience of illustration;

FIG. 8 is a front view of the guide;

FIG. 9 is a rear view of the guide;

FIG. 10 is a perspective view of the guide;

FIG. 11 is a bottom plan view of the guide;

FIG. 12 is a top plan view of the guide; and

FIG. 13 is an enlarged fragmentary rear elevational view thereof.

The dominant feature of my design resides in the guiding and water sealing structure.
